UNITED STATES PATENT OFFICE.

ERNEST A. HAND AND FREDERICK A. WYGANT, OF HORNELL, NEW YORK, ASSIGNORS
TO THE A. J. DEER COMPANY, INCORPORATED, OF HORNELL, NEW YORK, A COR-
PORATION OF NEW YORK.

ARTICLE HOLDER FOR SLICING MACHINES.

Application filed February 8, 1919. Serial No. 275,745.

To all whom it may concern:

Be it known that we, ERNEST A. HAND and FREDERICK A. WYGANT, a subject of the King of England and a citizen of the United States, respectively, residing in Hornell, in the county of Steuben and State of New York, have invented new and useful Improvements in Article Holders for Slicing Machines, of which the following is a specification.

This invention relates to a device for holding in a slicing machine the article which is being operated upon and more particularly to a holder in which the article is gripped at its rear end so as to permit of cutting this article into slices to the extreme rear end of the same.

This invention has for its objects to provide a holder of this character which is so constructed that a firm and reliable grip may be obtained on the rear end of the article; to so construct the holding device that the last particle will be retained in shape of a salable slice instead of becoming broken and unsalable; to so organize the holding means that interference with the cutter is positively prevented; to so construct the holding device that the same can be readily removed from the slicing machine while the article is attached to the holder so as to permit the slicing machine to be used for cutting other articles and then permitting of again replacing the holder with the article attached thereto without liability of changing the thickness in the slices which are cut from the article; and to provide simple and efficient means whereby this holder may be readily attached to the upright pillars of the different types of slicing machines.

In the accompanying drawings:

Figure 1 is a sectional elevation of the article holder or grip embodying our improvements. Figure 2 is a fragmentary rear elevation of the same. Figure 3 is a horizontal section, taken on line 3-3, Fig. 1. Figure 4 is a vertical section taken on line 4-4, Fig. 2, showing the gripping or engaging devices in their operative or extended position. Figure 5 is a similar view showing the gripping or engaging devices in their inoperative or retracted position. Figure 6 is a vertical section taken on line 6-6, Fig.

2, showing the gripping or engaging devices in their projected or operative position. Figure 7 is a similar view showing the gripping or engaging devices in their retracted or inoperative position. Figure 8 is a fragmentary perspective view of one set of gripping hooks and the head carrying the same.

Similar characters of reference refer to like parts throughout the several views.

1 represents the table upon which the article 50 to be sliced is supported on its underside, and 2 the cutter arranged adjacent to the front end of this table and adapted to cut off slices successively from the front end of this article. The article to be sliced is represented by dotted lines in Fig. 3 and may consist of any material which is usually served in slices, such for instance as ham sausage, dried beef, venison, etc. The cutter may be of any suitable construction although the same preferably has the form of a disk like those now in common use which are rotated while engaging the material to be cut. Means are also provided for moving the supporting table 1 and the cutter 2 one relatively to the other in a direction parallel with the plane of the cutter, but as this forms no part of the present invention no specific reference to the same is deemed necessary.

Our improvements relate more particularly to the means whereby the article to be sliced is gripped or held at its rear end while in the slicing machine and when removed therefrom, and in their preferred embodiment as shown in the drawings, the same are constructed as follows:

5 represents a feed plate or gripper carriage which is mounted on the supporting table 1 so as to move with the same in the direction parallel with the cutter but capable of sliding on this table in a direction perpendicular of the plane of the cutter for the purpose of advancing the article holding devices thereon together with the article held thereby toward the cutting line. Adjacent to its opposite longitudinal edges this gripper carriage is provided with two posts or pillars 3, 3 which are secured at their lower ends by screw fastenings 4, 4 to the feed plate and are preferably of rectangular form in cross section. Between these two posts

and above the adjacent part of the feed plate is arranged a supporting frame which is of substantially rectangular form and provided with upper and lower horizontal bars 9, 10, 5 and two upright bars 11, 11 connecting opposite ends of the horizontal bars. On its outer side one of the upright bars of the supporting frame is provided with locking lugs 12, 12 arranged adjacent to the upper 10 and lower edges of this frame, each of these lugs being provided on its outer side with a notch or groove 13 which is adapted to engage with the inner side of the adjacent post 3, for clamping the holder frame on this 15 post. On its opposite vertical bar this frame is provided about midway between its upper and lower edges with a laterally projecting locking lug 14 which has its outer edge provided with a rabbet 15 engaging 20 with the inner and rear sides of the opposite post 3 of the feed plate. 18 represents a rock shaft journaled lengthwise of the feed plate in a bearing on the locking lug 14 and provided at its front end with an eccentric or cam 16 engaging with the inner 25 side of the adjacent post 3 and also provided at its front end with a retaining flange 17 which engages with the front side of this last mentioned post. The turning of this 30 rock shaft together with the cam and retaining flange thereon is effected by means of a handle 19 applied to the rear end of the rock shaft and engaging with the rear side of the adjacent locking lug, as best shown in 35 Figs. 2 and 3. By means of these clamping devices the supporting frame and the means whereby the article to be sliced is detachably connected therewith may be quickly and easily attached to the posts of the feed plate 40 as well as removed therefrom. By this means the holder may be detachably mounted in different types of slicing machines.

7 represents a breast plate which is arranged in front of the supporting frame in 45 a vertical position and against the front side of which the article to be sliced is held for presenting the same to the cutter. Formed in said breast plate are a plurality of vertical slots 22, 23 which are preferably 50 arranged in horizontal rows one above the other. The number of these rows may vary but as shown in the drawings three of such rows are employed.

Through these slots gripping hooks 20, 21 55 are adapted to extend for the purpose of engaging with the rear end of the article to be sliced and clamping the same against the breast plate or releasing said article, each of these gripping hooks being preferably inclined or curved vertically from its rear end or base to its front end or beak. The means whereby the hooks are actuated are preferably so constructed that the same have a movement parallel with the front face of the 60 breast plate. In order to increase the grip-

ping effect of these hooks on the article which is to be sliced some of the hooks are pointed upwardly and others downwardly so that when a plurality of such oppositely pointed hooks engage the rear end of the article to be mounted the latter will be held reliably against upward and downward movement relatively to the breast plate and thereby insure accurate and uniform operation of the machine. In the preferred organization of this device the hooks which pass through each horizontal row of slots 22, 23 are arranged in two sets the members 21 of one set projecting downwardly and alternating with the members 20 of the other 70 set which project upwardly. The members of each set of hooks are preferably connected at their rear ends with a head or bar 28 which for convenience is made integral with these teeth, as shown in Fig. 8, although the 75 same may be otherwise constructed if desired. The gripping hooks have their heads connected in any suitable manner with horizontal shifting bars 24, 25 which are arranged between the rear side of the breast 80 plate and a plurality of upright intermediate frame bars 29 connecting the rear edges of the upper and lower bars 9, 10, of the supporting frame. The several hook supporting bars 24, 25 alternate with each other 85 in a vertical direction in rear of the breast plate and those bars 25 which carry the upwardly pointing gripping hooks 20 are connected with each other by means of upright connecting bars 27, 27, while those bars 24 which carry the downwardly pointing hooks 21 are connected with each other by upright 90 bars 26, 26. These upright bars 26, 27 and horizontal bars 24, 25 carrying the hooks 21, 20, form two carriers. The upright bars 95 of each hook carrier engage with the rear sides of the horizontal bars of the other hook carrier so that these two hook carriers are capable of sliding vertically one relatively to the other. When the hooks of both 100 sets are in their fully retracted position relatively to the breast plate the vertical movement of the two carriers may be limited relatively to each other in one direction by some of the horizontal bars 24 of one set engaging with one side of some of the horizontal bars 25 of the other set, as shown in 105 Fig. 7, and when the hooks are in their fully projected position the vertical movement of the hook carriers in the opposite direction 110 may be limited by the opposite sides of some of the horizontal bars of one carrier engaging with the opposing sides of the horizontal bars of the other hook carrier, as shown in 115 Fig. 6.

The vertical reciprocating movement of the carriers which support the oppositely pointing groups of hooks may be effected in various ways, for instance, as shown in the drawings, by means of a rock lever 30 pivot- 120

125

130

ed on the central rear bar 29 of the supporting frame, so as to be capable of swinging in a vertical plane parallel with the breast plate and provided on opposite sides of its 5 axes with radial slots 33 which receive coupling pins or screws 31, 32 one of which is connected with one of the hook carriers while the other is connected with the other hook carrier. Upon rocking this lever in 10 one direction, the carrier of the downwardly pointing hooks 21 will be moved downwardly and the other carrier which supports the upwardly-pointing hooks 20 will be moved upwardly, and vice versa.

15 Means are provided for imparting a horizontal backward and forward movement of the breast plate so as to cause the impaling or gripping hooks or pins to be either projected relative to the face of this plate for 20 gripping the article to be sliced or retracted for releasing said article. The preferred means for accomplishing this purpose comprise two upright cam plates or bars 42 secured to the rear side of the breast plate 25 adjacent to the inner side of the vertical bars 11, 11, of the supporting frame, each cam bar being provided at its upper and lower ends with cam-shaped slots. The upper cam slot of each of the cam bars is provided with an upright central part 36, a 30 comparatively long upper rearwardly trending outer part 37 connected with the upper end of the central part and a comparatively short rearwardly trending inner part 38 connected with the inner end of said central part. The lower cam slot of each of these cam bars comprises a vertical central part 39, a comparatively long rearwardly trending outer part 40 connected with the outer end of 35 said central part, and a comparatively short rearwardly trending inner part 41 connected with the inner end of said central part 39. The uppermost horizontal bar 24 of the carrier which supports the downwardly 40 pointing gripping hooks 21 is provided at its opposite ends with laterally projecting shifting pins 34 which engage with the upper cam slots of the cam bars and the lowermost horizontal bar 25 of the other carrier which supports the upwardly-pointing hooks 20 is provided at its opposite ends with laterally projecting shifting pins 35 which engage with the lower cam slots of 45 said cam bars.

50 Upon turning the lever into the position shown in Figs. 1, 2, 3, 4 and 6 the carrier supporting the hooks 20 is moved upwardly and the carrier supporting the hooks 21 is moved downwardly, whereby the upper 55 and lower shifting pins 34, 35 move inwardly through the long inclined outer parts 37, 40 of the cam slots, thence through the upright parts 36, 39 thereof, and thence through the short inner inclined parts 38, 41 60 of the same.

By this means the breast plate is shifted from its forward position in which its front face is arranged beyond the points of the pins or hooks 20, 21, as shown in Figs. 5 and 7, to its rearward position in which its front face is arranged behind the points of said hooks, as shown in Figs. 4 and 6. When moving the hooks and breast in this manner while a piece of meat or other article to be sliced is held against the front 75 side of the breast plate, these hooks will embed themselves in the meat as the breast plate recedes by entering the meat obliquely during the initial part of the vertical movement of the hooks during which time the 80 shifting pins are moving the long outer parts 37, 40, of the cam slots, during the intermediate part of the vertical movement of these hooks the breast plate remains at rest owing to the shifting pins 34, 35 engaging with the vertical parts 36, 39 of the cam slots, whereby the hooks produce a wedge action on the meat which draws the latter against the breast plate, and during 85 the last part of the movement of the shifting pins in this direction the same engage the reversely inclined inner parts 38, 41, of the cam slots whereby the breast plate is again advanced slightly so as to cause the same to press the meat forwardly 90 against the rear sides of the hooks and clamp the same firmly in place. A movement of these parts reverse to that just described will release the article from the 95 hooks and breast plate.

By this means the article to be sliced can be held securely at its end up to the last slice so that the latter when removed from the hooks and plate is thin enough and unbroken and as salable as the previous slices 100 cut from the article, thereby avoiding waste or reducing the profit on a particular article which is dispensed in the form of slices.

Whenever it is desired to use the slicing machine for other purposes which necessitates removing temporarily the end gripping mechanism, this can be done while the article which is being sliced is still attached to the gripping device, and it also permits this gripping device to be again mounted 110 in the slicing machine and the article to be returned to its normal position, so that the slicing of the same can be resumed without any variation in the thickness of the slices.

Owing to the angular position of the 115 gripping hooks relatively to the face of the breast plate, a wedge-like action of these hooks is produced on the article whereby the same is firmly pressed against the breast plate and held in reliable engagement therewith so that the slices may be cut uniformly and properly therefrom.

We claim as our invention:

1. An article holder for slicing machines comprising a breast plate provided with a 120

front bearing face with which the article to be sliced is adapted to engage, and having a movement perpendicular to said face but held against movement in a direction parallel with said face, and a gripping hook co-operating with said face and having a movement parallel thereto but held against movement in a direction perpendicular to said face, and the front end of said hook being arranged in rear of the face of said breast plate when the latter is in its projected position.

2. An article holder for slicing machines comprising a breast plate provided with a front bearing face with which the article to be sliced is adapted to engage, and having a movement perpendicular to said face but held against movement in a direction parallel with said face, and an inclined gripping hook co-operating with said face and movable parallel relatively thereto, but held against movement in a direction perpendicular to said face, and the front end of said hook being arranged in rear of the face of said breast plate when the latter is in its projected position.

3. An article holder for slicing machines comprising a breast plate provided with a front bearing face with which the article to be sliced is adapted to engage and having a movement perpendicular to said face, a support arranged in rear of said plate and having a movement parallel with said face, but held against movement in a direction perpendicular to said face; and an inclined gripping hook mounted on said support and adapted to cooperate with the face of said plate and the front end of said hook being arranged in rear of the face of said plate in the projected position of the latter.

4. An article holder for slicing machines comprising a breast plate provided with a front bearing face with which the article to be sliced is adapted to engage and movable perpendicular to its face but held against movement in a direction parallel with said face, and two gripping hooks which move in opposite directions parallel to said face and adapted to co-operate therewith for gripping and releasing the article to be sliced, but held against movement in a direction perpendicular to said face, and the front ends of said hooks being arranged in rear of the face of said plate in the projected position of the latter.

5. An article holder for slicing machines comprising a breast plate having a front bearing face which is adapted to be engaged by the article to be sliced and movable perpendicular to said face, a cam arranged on said plate, a carrier movable parallel with said face and having a pin engaging with said cam, and a plurality of gripping hooks mounted on said carrier and adapted to co-operate with said bearing face.

6. An article holder for slicing machines comprising a breast plate having a front bearing face which is adapted to be engaged by the article to be sliced and movable perpendicular to said face, cams arranged on said plate some of which trend in one direction and others in the opposite direction, two carriers movable parallel to said face and having pins engaging said oppositely trending cams, and hooks arranged on said carriers and co-operating with said bearing face for clamping the article to be sliced.

7. An article holder for slicing machines comprising a breast plate having a front bearing face which is adapted to be engaged by the article to be sliced and movable perpendicular to said face, cams arranged on said plate, some of said cams trending in one direction and others in the opposite direction, two carriers movable parallel to said face and having pins engaging said cams, hooks mounted on said carriers and co-operating with the face of said plate, and means for actuating said carriers comprising a rock lever connected on opposite sides of its axis with said carriers.

8. An article holder for slicing machines comprising a frame provided on its rear side with supporting bars, a breast plate mounted in said frame in front of said bars and provided with a plurality of slots and a front face, cams arranged on said plate some of which trend in one direction and others in the opposite direction, two carriers arranged between said supporting bars and breast plate and having pins engaging said cams, and gripping hooks mounted on said carriers and adapted to project through said slots and co-operate with the front face of said breast plate.

9. An article holder for slicing machines comprising a frame provided on its rear side with supporting bars, a breast plate mounted in said frame in front of said bars and provided with a plurality of slots and a front face, cams arranged on said plate some of which trend in one direction and others in the opposite direction, two carriers arranged between said supporting bars and breast plate and having pins engaging said cams, gripping hooks mounted on said carriers and adapted to project through said slots and cooperate with the front face of said breast plate, and a rock lever pivoted on one of the supporting bars of said frame and connected on opposite sides of its fulcrum with said carriers.

10. An article holder for slicing machines comprising a frame provided on its rear side with supporting bars, a breast plate mounted in said frame and provided with a plurality of slots, cams arranged on said plate and trending in opposite directions, two carriers arranged between said supporting bars and breast plate and comprising a plurality of

horizontal supporting bars and a plurality of upright connecting bars secured to the rear side of said supporting bars, the connecting bars of each carrier engaging with the rear side of the supporting bars of the other carrier, and a plurality of gripping hooks mounted on the supporting bars of each carrier and projecting through said slots in the breast plate, the hooks of one carrier inclining in one direction and the hooks of the other carrier inclining in the opposite direction.

11. An article holder for slicing machines comprising a breast plate having a face, a hook movable parallel to the face of said plate and adapted to engage and release an article resting against the face of said plate and actuating means for operating said plate constructed to retract the same during the initial part of the advancing stroke of said hook, then retaining the plate at rest during the middle portion of the advancing stroke, and then partially projecting said plate during the final part of the advancing stroke of said hook.

12. An article holder for slicing machines comprising a breast plate perpendicular to its face, a hook movable parallel to the face of said plate and adapted to engage and release an article resting against the face of said plate, and actuating means for operating said plate constructed to retract the same during the initial part of the advancing stroke of said hook, then retaining the plate at rest during the middle portion of the advancing stroke, and then partially projecting said plate during the final part of the advancing stroke of said hook, said actuating means comprising cam bars arranged on said plate and provided with cam slots each of which has a vertical central part which is parallel to the face of said breast plate, a comparatively long inclined outer part connecting with the outer end

of said central part and a comparatively short inclined inner part connecting with the inner end of said central part, and shifting pins moving with said hook and engaging with said cam slots.

13. An article holder for slicing machines comprising a horizontal supporting plate provided with two upright posts, a breast plate against which the article to be sliced is clamped, a notched locking lug arranged on one end of said breast plate and engaging its notch with the inner side of one of said posts, a rabbetted locking lug arranged on the opposite end of said breast plate and engaging with one side of the other post and a locking cam pivotally mounted on the rabbetted lug and having a flange engaging with the last mentioned post opposite to the rabbetted lug and a cam face which engages the inner side of said last mentioned post.

14. In combination, a plate having a plurality of openings therein, prongs arranged to project through said plate at an oblique angle to the surface thereof, and means for shifting said prongs relative to said plate in a direction parallel thereto to cause said prongs to engage material to be sliced.

15. In combination, a plate having openings therein, prongs projecting through said plate and arranged at an oblique angle to the face thereof, some of said prongs being inclined in one direction and others of said prongs being inclined in an opposite direction relative to said surface, and means for shifting said prongs in the direction of their inclination and parallel with said plate to cause said prongs to enter material to be sliced and to draw said material against the surface of said plate.

ERNEST A. HAND.
FREDERICK A. WYGANT.
